(57) **CLAIM**

The ornamental design for an asymmetrical trowel, as shown and described.

DESCRIPTION

FIG. 1 is a top-right perspective view of an asymmetrical trowel showing my new design;

FIG. 2 is a bottom-left perspective view thereof;

FIG. 3 is a top plan view thereof;

FIG. 4 is a bottom plan view thereof;

FIG. 5 is a right elevation view thereof;

FIG. 6 is a left elevation view thereof;

FIG. 7 is a front elevation view thereof; and,

FIG. 8 is a rear elevation view thereof.

The broken lines shown in the figures are environmental structures and form no part of the present claim.

1 Claim, 4 Drawing Sheets

FIG. 3
